UNITED STATES PATENT OFFICE.

ROBERT C. RUSSELL, OF PITTSBURGH, PENNSYLVANIA.

LOOSE-LEAF BOOK.

Application filed July 28, 1925. Serial No. 46,604.

To all whom it may concern:

Be it known that I, ROBERT C. RUSSELL, a citizen of the United States, and resident of Pittsburgh, in the county of Allegheny and State of Pennsylvania, have invented certain new and useful Improvements in Loose-Leaf Books; and I do hereby declare the following to be a full, clear, and exact description of the invention, such as will enable others skilled in the art to which it appertains to make and use the same.

This invention relates to improvements in loose leaf books, and more particularly to that type in which the members which pass through the leaves are connected with the covers of the book through the medium of longitudinally movable devices which cooperate with the leaf-penetrating members to lock them normally in position.

An object of my present invention is to provide loose leaf securing devices which shall be simple in construction; which shall provide positive and effectual locking means, and which shall be readily operable to release a leaf or leaves or to facilitate the insertion of a leaf or leaves.

With this and other objects in view, the invention consists in certain novel features of construction and combination of parts as hereinafter set forth and pointed out in the claims.

In the accompanying drawings;

Figure 1 is a face view showing the back and cover members of a book and illustrating the application of my improvements;

Figure 2 is a view in section on the line 2-2 of Figure 1;

Figure 3 is a view in section on the line 3-3 of Figure 1;

Figure 4 is a fragmentary view partly in elevation and partly in horizontal section, and

Figure 5 is a view of a key which may be employed for manipulating the locking devices.

The cover members of a book are indicated, 1, 1, and the back member at 2. To each cover member, a plate 3 is secured, and

each plate is bent upon itself in a manner to provide tubular portions or sleeves 4 which overlie the respective edge portions of the back member 2. The overlying portions of the plates 3 in rear of the tubular or sleeve portions 4 are sufficiently spaced apart to provide ways for the accommodation of locking bars 5. Each bar 5 may be made flat in cross section and each is provided at intervals with offset pins 6 disposed parallel with and spaced from the bar,—one pin on each bar being made slightly longer than the pin or pins in advance of the same, and the pins 6 are movable in the tubes or sleeves 4 and are adapted to be made to extend across notches 7 in said tubes or sleeves.

Links or bars 8 pass through suitable openings in the base portions of the leaves 9 of the book and at their ends, said links are formed with eyes 10 which enter the tubes or sleeves 4 so as to align with the bases of the latter and receive the pins 6 on the locking bars 5 when the latter are moved longitudinally in a manner to cause said pins to span the notches 7 in said tubes.

In the embodiment of the invention shown in the drawings, two locking bars are provided at each of the edge portions of the back member 2 and the inner edge portions of the respective cover members 1, but if desired, locking bars may be provided at one side only of the back and the links hinged to the opposite cover member in any suitable manner.

The locking bars of each pair are provided with resilient fingers 11, 11 projecting relatively in reverse directions and the inner end portion of the finger on one locking bar is adapted to overlap the inner end portion of the adjacent locking bar. The overlapping portions of the fingers of the locking bars of each pair are formed with ratchet teeth, and the resilience of said finger is such that the ratchet teeth on said fingers are caused to intermesh when the fingers are in overlapping relation, thus securely locking said bars 5 and the pins 6 which they carry, against longitudinal movement. The

cross links 8 are therefore positively locked in place.

Each plate 3 is provided with a hole or socket 12 located over the overlapping portions of the locking fingers 11 of each pair of locking bars, and at respective sides of the paths of said fingers, each plate 3 is provided with holes 13, 13. The holes 12 and 13 are intended for the accommodation of a key 14, the latter being provided at one end with a central projection 15 to enter the hole 12, and with two bent lugs 16 to enter the holes 13 and become disposed at opposite sides of the resilient locking fingers respectively of the two locking bars. By now turning the key on the projection 15 as a fulcrum, the lateral pressure in opposite directions on the locking fingers by the lugs 16, will cause the intermeshing portions of said fingers to be separated and therefore released from each other. The operator may now withdraw the locking bars (by engaging the end portions 17 thereof) distances sufficient to withdraw the pins 6 from the eyes 10 at one end of the cross links 8, thus releasing the latter. In again locking the cross links, it is simply necessary to insert perforated end portions thereof into the notches 7, and press the locking bars, respectively in opposite directions, when the pins 6 will enter the perforations in the links and the toothed fingers 11 will become interlocked automatically.

Having fully described my invention what I claim as new and desire to secure by Letters-Patents, is:—

1. In a loose leaf book, the combination with guide means, and cross links each having a perforated end portion, of a plurality of locking bars movable in the same guide means and provided with pins to engage the perforated end portions of said links, and means for locking said plurality of locking bars against relative movement in said guide means.

2. In a loose leaf book, the combination with guide means and cross links, of locking bars movable in said guide means and provided with means to engage the cross links, said locking bars having interlocking connection with each other, and means to release said locking bars from each other.

3. In a loose leaf book, the combination with guide means, and cross links each having a perforated end portion, of two locking bars movable in said guide means and provided with pins to engage the perforated end portions of said links, and means for interlocking said locking bars.

4. In a loose leaf book, the combination with guide means, and cross links each having a perforated end portion, of locking bars movable in said guide means and provided with pins to engage the perforated end portions of said links, means for inter-

locking said locking bars, and a key for operating said interlocking means to release said locking bars from each other.

5. In a loose leaf book, the combination with guide means, and cross links, each having a perforated end portion, of locking bars movable in said guide means and provided with pins to engage the perforated end portions of said links, interlocking members carried by said locking bars, the member on at least one of said locking bars being resilient and means for separating said members to release the locking bars.

6. In a loose leaf book, the combination with notched guide means, and cross links having perforated end portions to enter the notches of the guide means, of two locking bars movable in said guide means and provided with pins to extend across the notches in the guide means and through the perforated portions of said links, resilient fingers on said locking bars, the free end portion of the finger on one locking bar adapted to overlap the free end portion of the finger on the other locking bar, the overlapping portions of said resilient fingers having interlocking portions, and a key for separating said fingers to release the locking bars.

7. In a loose leaf book, the combination with notched guide means, and cross links having perforated end portions to enter the notches of the guide means, of two locking bars movable in said guide means and provided with pins to extend across the notches in the guide means and through the perforated portions of said links, resilient fingers on said locking bars, the free end portion of the finger on one locking bar adapted to overlap the free end portion of the finger on the other locking bar, the overlapping portions of the fingers of the two locking bars having intermeshing teeth, and means for separating said fingers to release said locking bars.

8. In a loose leaf book, the combination with notched guiding means, and cross links having perforated portions to enter the notches of the guiding means, of two locking bars movable in said guiding means and provided with pins to extend across the notches of the guiding means and through the perforated cross links, resilient fingers on said locking bars and having interlocking relation to each other, said guiding means having holes at respective sides of the fingers on the locking bars, and a key having projections to enter said holes and engage the respective fingers whereby turning of the key will cause separation of the resilient fingers to release the locking bars.

9. In a loose leaf book, the combination with notched guiding means, and cross links having perforated portions to enter the notches of the guiding means, of two locking bars movable in said guiding means and

provided with pins to extend across the holes and engage the respective fingers and 10 notches of the guiding means and through said key also having an intermediate projection to enter said intermediate hole, whereby turning of the key will cause separation of the resilient fingers to release the locking 15 bars.

In testimony whereof, I have signed this specification.

ROBERT C. RUSSELL.
